UNITED STATES PATENT OFFICE.

JOHANN VOKAC, OF VIENNA, AUSTRIA, ASSIGNOR TO EISENGIESSEREI CARL LUBER & SOHN, OF VIENNA, AUSTRIA, A COMPANY OF AUSTRIA.

MAGAZINE AND SLOW-BURNING STOVE.

Application filed November 29, 1926, Serial No. 151,506, and in Austria September 21, 1926.

This invention relates to improvements in magazine- and slow-burning stoves of the kind in which in a fuel-shaft or magazine the fuel is at first distilled by an air-current admitted at the top end and the gases discharged through the magazine-grate are subjected to combustion outside the grate, and subsequently the distilled fuel is subjected to complete combustion by an air-current admitted at the bottom end.

The mode of supplying air to the stove is of the greatest importance for the proper working of the same. In case air of combustion is introduced at a few places only a kind of nozzle-action is produced also in large places and the fuel does not burn uniformly, but hollow spaces interrupting the combustion are the result of a quicker burning down of the fuel at those places, which are directly met by the air current. It has been found to be of advantage to introduce the air concentrically with the axis of the magazine through an adjustable circular opening. In order to prevent the gases from escaping through this opening in the case of a reduced draft it is necessary to provide a space round the circular opening for the reception of any accumulated gases, which extends upward from the said opening and from which these gases can pass into the chimney.

One mode of carrying out the present invention is illustrated by way of example on the accompanying sheet of drawings in which:

Fig. 1 shows a stove in sectional elevation, and

Fig. 2 is a perspective view of a detail constructed according to the invention.

The fuel-receptacle or magazine 7 is vertically arranged in a shell or casing 1 and a distillation-grate 11 of semi-spherical shape is attached to the bottom end of the former. An inner casing 17, disposed underneath the magazine 7, is provided with a plane grate 15 and fresh air can be supplied to the bottom side of the latter by way of an adjustable opening 6 in the door 5. The top end of the stove is closed by a cover 24, provided with an adjustable opening for the supply of air from the top during the period of distillation, the burnt gases being discharged by way of the chimney-pipe 2. After the distillation has taken place air, which is heated by the hot lower portion of

the stove, is supplied from the bottom, while the gases of combustion now generated are passed off by way of the chimney-pipe 29, which establishes communication between the cover 24 and the chimney. The direction of the draft can be reversed by operating dampers 34 and 35, disposed in the chimney-pipes 29 and 2 respectively and mounted on a common shaft 32 in such a manner, that they are displaced at 90 degrees with respect to each other.

The top end of the stove is closed by the cover 24, provided with a hopper 25, which is centrally disposed above the magazine of the stove and concentrically with respect to the axis of the latter. The hopper is of such a depth, that its bottom opening terminates below the chimney-pipe 29. Owing to this arrangement the smoke rising from the magazine cannot escape through the opening, but is accumulated in the top space around the hopper and escapes through the chimney-pipe 29. The bottom of the hopper is closed by a dish-shaped member 26, in which the evaporation-water is collected. The following arrangement serves for regulating the air-supply opening between the mouth of the hopper and the dish-shaped member 26:

The member 26 is suspended from the perforated lid 37 of the hopper by means of a rod 36, passing through the said lid. In the middle of the lid are centrally disposed three pairs of steps 38', 38'', 38''' of different height, the two steps of each pair being disposed diametrically opposite each other and are of the like height. A cross member 38, secured to the rod, rests on opposite steps. The dish-shaped member 26 can be suspended from the desired pair of steps by lifting and rotating the former by means of a knob secured to the rod 36, so that the annular clearance can be adjusted according to requirement or fully closed. In order to charge the stove it is necessary to remove the dish-shaped member and the lid.

The diameter of the upper chimney-pipe 29 is smaller than the diameter of the bottom chimney-pipe 2 and consequently also the diameters of the dampers 34 and 35 differ with respect to one another. Owing to this construction the conditions of the draught and the quantity of the supplied air are automatically adapted to the different requirements of both phases of operation.

The shell or casing of the stove is subjected to different temperatures in the different regions. The part of the casing from the basket-shaped grate downwards is strongly heated during the period of gasification, while the upper part of the same remains considerably cooler. Particularly if the shell or casing consists of cast-iron the same may easily burst owing to the irregular distribution of the heat stresses. According to the present invention this danger is avoided in that the shell or casing consists of two parts, which are united by a joint substantially in the height of the flange of the basket-shaped grate.

I claim:

1. A magazine- and slow-burning stove comprising in combination a casing, a chimney-pipe at the top, a chimney-pipe at the bottom, a damper mounted in each pipe, an air-supply means in the lower part of the stove, a hopper centrally disposed with respect to the magazine, a perforated lid for the hopper, a dish-shaped member for closing the discharge opening of the hopper, and
- 20
- 25

means for adjusting the dish-shaped member with respect to the hopper, for the purpose specified.

2. A magazine- and slow-burning stove according to claim 1, in which the means for adjusting the dish-shaped member consists of pairs of steps of different height secured to the perforated lid, the two steps of each pair being disposed diametrically opposite each other and are of like height, a rod passing through the lid and to the bottom end of which is secured the dish-shaped member, and a cross-bar secured to the said rod, for the purpose specified.

3. A magazine- and slow-burning stove according to claim 1, in which the chimney-pipe at the top and its damper are smaller than the chimney-pipe at the bottom and its damper.

4. A magazine- and slow-burning stove according to claim 1, in which the casing consists of two parts which are united by a horizontal joint.

In testimony whereof I affix my signature.
JOHANN VOKAC.
